UNITED STATES PATENT OFFICE.

FRED M. CARROLL, OF ENDICOTT, NEW YORK, ASSIGNOR TO THE TABULATING MACHINE COMPANY, OF ENDICOTT, NEW YORK, A CORPORATION OF NEW JERSEY.

CARD-CONTROLLED PRINTING MACHINE.

Application filed December 12, 1922. Serial No. 606,364.

This invention relates to a perforated record controlled machine and has for its main object the provision of a machine which will print alphabetical characters upon a record sheet under the control of perforated records. The present invention is further directed to the improvement of the machine shown in my Patent No. 1,516,079, dated November 18, 1924, to the general end that alphabetical characters may be printed. Further provision is made for printing either alphabetical characters or digit characters or both under the control of perforated records. In the machine previously patented by me heretofore mentioned the records which were handled by the machine were the usual Hollerith tabulating cards in which a separate hole or index point was provided for each digit and for each controlled type. Obviously such an arrangement is impractical in a machine which is intended to print the letters of the alphabet either alone or with the digits inasmuch as the record card would be too large for ready commercial use. In printing alphabetical characters resort has previously been had to combinational holes for representing the letters of the alphabet. However, such previous machines have been comparatively complicated in their nature usually requiring that the record card be held stationary at the time sensing or analyzing was effected so that the speed of operation of the machine was reduced. Furthermore, the printing devices heretofore used with such machines were of a type which employed a differentially positioned type carrier which employed an idle restoring movement. According to the present invention I provide means whereby the printing devices of my former patent may be utilized for printing alphabetical characters with or without digits as well and furthermore I provide means for sensing records of combinational form and for controlling and calling into action and printing devices under the control of the combinational hole records. Sensing of the records is preferably effected while they are in continuous motion through the machine and printing operations are also effected with the parts and type in continuous movement past the printing point. Pro-

vision is made for securing much higher speeds than heretofore possible in machines which effected printing of alphabetical characters under the control of perforated records and more particularly perforated records of combinational hole form.

A further object of the present invention resides in the provision of a plurality of type elements representing letters of the alphabet either alone or in with digit representing type together with means for continuously advancing the type toward printing position together with the provision of means for selectively calling the type for printing operations under the control of perforated holes in record cards of combinational form. While in the particular embodiment of the invention herein illustrated I have shown these combination records as being formed with two hole perforations variously located in the card field the invention is not limited in its broad aspects to such forms of perforations but these may comprise other combination forms now known to those skilled in the art.

Referring to the drawings wherein I have shown what I now consider to be one and the preferred embodiment of my invention:

Fig. 1 is a sectional elevation of the printing portion of my machine taken on line 1—1 of Fig. 2.

Fig. 2 is a plan view of a portion of the machine, the rest of the machine being broken away.

Fig. 3 is a fragmentary detail showing the operation of one of the printing or type elements of the machine.

Fig. 4 is a fragmentary sectional plan view of a portion of the type restoring mechanism.

Fig. 5 is a side view of the mechanism shown in Fig. 4.

Fig. 6 represents a card of the Hollerith type, punched for use in the present machine.

Fig. 7 is a wiring diagram.

As is well known, the Hollerith card is provided with a plurality of vertical rows or columns of index points, usually numbered from 0 to 9. In such case each column has ten digit values; and a hole punched at one of these index points will, when the card

is run through the proper machine, cause a reproduction of that digit value in some form, usually by printing the digit or by exhibiting the same on a counter wheel or 5 by accumulating the same in counter wheels along with other received digit values.

In the present invention I may use the standard Hollerith card provided with columns of ten index points to represent, not only the digits, but also the entire alphabet and other arbitrary characters. According to my system, instead of perforating but one hole in each column of index points, I perforate two holes which taken together form a 10 combinational hole designation. The first hole, according to its position, serves to designate which of several groups of characters contains the character to be selected, and the second hole designates which of the several 15 characters in the designated group is to be selected. Mechanism is then brought into 20 operation to print such characters.

In describing my invention I have illustrated it in connection with mechanisms 25 more specifically disclosed in my Patent No. 1,516,079, dated November 18, 1924.

In Figs. 1 and 2 are shown a circular type carrying member or drum 1, having a plurality of type bars 2, pivoted at 3, Fig. 3. 30 The drum is mounted for rotation on a shaft 4 and turns in the direction of the arrow in Fig. 1, so that the type bars pass the printing position in rapid succession. At the printing position are the usual inking ribbon 5 and the platen 6. Adjacent the type bar in its printing position is a hook member 7 adapted when actuated to move into the path of a hooked portion 8 of the type bar to cause the type to be impelled 35 against the ribbon to effect printing. The hook 7 is shown pivoted at 9 and is adapted to be actuated by a collar 10 on a rod 11. Said rod is attached at its lower end to a bell crank 12, Fig. 7, pivoted at 13 and adapted to be locked in inoperative position 40 by the armature 14 of an electromagnet 15. The armature and the bell crank are so interconnected by a spring 16 that the armature is normally urged toward locking 45 position and the rod or call wire 11 will be raised to operative position when released by the armature. At the proper time in the cycle of the machine as determined by the ratio of the interconnecting gearing, a releasing cam 16 rotating clockwise as seen in 50 Figs. 1 and 7 will engage rod 11 and, moving it to the left, release the hook 7 so that it may return to inoperative position, releasing the impelled type bar and moving out 55 of the path of the hook on the next type bar. In this connection the partition rings 27 between the type bars are provided with notches 27^a having an inclined edge as at 27^b, Fig. 3. The end of the hook 7 may be 60 sufficiently wide to extend over one of these

partition rings so that when it is moved to type-actuating position, dipping into one or the notches 27^a to engage the type bar, it will immediately thereafter be lifted by the incline 27^b to inoperative position. A spring 70 7^a may be employed to hold the hook 7 normally in inoperative position. The cam 16 is rotated by a pinion 17 connected through gears 18, 19, 20 to a gear 76 hereinafter referred to. At the proper time a bail 22 turning clockwise will engage a collar 23 on rod 11 and depress the same, so that the armature 14, being at that time deenergized, will lock the rod down. The details of operation of the restoring bail are more specifically shown in my aforesaid copending application.

As shown in Fig. 2, the type bars 2, besides being arranged circumferentially about the drum, are arranged in a plurality of 85 parallel planes, each plane corresponding to and being controlled by one of the columns 24 of index points on the card 25, Fig. 7.

As will be readily seen in Figs. 1 and 3, the carrier drum includes a central member 90 26, upon which are mounted the spacing and supporting flat rings 27 between each plane of type bars. The rings are slid into place upon the member 26 over the transverse ribs 28 and then turned slightly through grooves 95 in the ribs so that the notches 29 take the position shown and the rings will be held against lateral displacement. Rods 3 reaching through the several spacers 27 serve to support the type bars. Additional rods 30 100 serve to support the restoring cams 31. There is one of these cams for each type bar. The cams are fixed upon the bars and each bar is provided at one end with a pinion 32 meshing with a circumferential gear rack 33 105 mounted in bearing guides 34. On one of the rods 30 is another pinion 36 meshing with an idler 37 which, in turn, meshes with a pinion 38 encircling shaft 4 but fixed to the frame member 38^a. This train of gearing 110 serves to cause rotation of all of the cams 31. The timing of such rotation with respect to the rotation of the drum 1 as a whole is such that the circumference of the cam rests against the type bar, as at 39, during the greater portion of a revolution of the drum, holding the type bar in inoperative position; releasing it by reason of the position of the recessed portion 40, Fig. 3, 115 in time to permit it to move to printing position if actuated by the hook 7, and thereafter, by reason of the hooking effect at 41, return the type bar to inoperative position.

In Fig. 7 the card 25 is shown as being fed by rollers 42. The card is fed in this manner successively past several sensing stations designated A to F inclusive. Each of these stations is provided with the usual Hollerith contact brushes 43 adapted to engage the contact block 44 when a perfora- 120 125 130

tion in the card passes between the brush and block. In Fig. 2 the shaft 4 is shown as carrying a slip ring 45 engaged by a brush 46. The ring carries insulating blocks 47 over which another brush 48 operates and between which projections 49 on the ring reach so that periodically in the rotation of the ring the brush 48 will pass over these projections and thus be electrically connected with brush 46 through the medium of the ring 45. On the same shaft with gear 19, which is actuated through gear 20, is a drum 51, the surface of which may be of insulating material in which are embedded several contacts 52 and a slip ring 53. The contacts 52 are stepped successively around the drum, as indicated, and each is adapted to cooperate with one of the several brushes 54, while the ring 53 cooperates with brush 55. As shown in Fig. 7, the several contacts 52 are electrically connected to the ring 53. The spaces between the contact projections 49 represent separate groups of digit and alphabet characters as illustrated diagrammatically. These groups are designated A' to F' inclusive, and each of the characters contained therein represents one of the type bars of each circumferential set shown in Figs. 1 and 2.

The machine may be started in the following manner: Closure of switch 70 will cause motor 71 to operate. The shaft 72 of said motor may carry a worm 74 meshing with a worm wheel 75 on the same shaft 73' with a gear 76 which meshes with gear 20, which in turn meshes with gear 21 on shaft 4 to turn drum 1, etc. Thus, when the motor operates, the shaft 4 and all parts geared thereto will be driven. The shaft 73' is shown as connected with a clutch 73 adapted to clutch the card feed shaft 73' to shaft 73' to effect card feeding. No attempt is made here to show the details of construction of the clutch 73, such devices being common in this art, and it being sufficient to state that the usual one way clutch which is normally inoperative and which is brought into and maintained in operation by an electromagnet may be employed. The magnet for this purpose is shown at 77 in the wiring diagram. The circuit through this magnet is normally open, so that when the switch 70 is closed the machine operates without feeding cards. Depression of the start key 78 will now close contacts 79 and complete a circuit through the clutch magnet as follows: From the supply lines 56 through wire 80, contacts 79, a circuit holding magnet 81, clutch magnet 77, and back through wire 82 to the other side of the line. The energization of magnet 81 will close contacts 83 so that when the key 78 is released and contacts 79 open the clutch magnet circuit will continue closed; the current still flowing through magnet 81 to keep contacts 83 closed. The operation of clutch 73 has now brought the card feeding mechanism into operation and the cards begin to feed down between the feed rollers 42. The feeding mechanism is more specifically disclosed in my aforesaid application. When the cards reach the card lever 84 and close contacts 85 in the well known manner a circuit is established from the line through wires 80, 86, magnet 87, wire 88, any one of contacts 85 and back to the other side of the line. Magnet 87 now closes contacts 89 and establishes a circuit around the holding magnet 81 and through the clutch magnet; the current passing from wire 80 through wire 86, contacts 89 and magnet 77. There being less resistance through this shunt circuit, magnet 81 will lose its energy and permit contacts 83 to open. The maintenance of the operation of the card feed mechanism is now dependent upon the continuous flow of cards to hold contacts 85 closed. When the last card passing through the machine passes the last card lever 84 and permits contact 85 to open, magnet 87 becomes deenergized, contacts 89 open, clutch magnet 77 becomes deenergized and the card feeding stops. The feeding of the card is so synchronized with the rotation of shaft 4 that, when it is passing through sensing position A the brush 43 will be passing over the index point position "9" at the same time that the brush 48 is passing over the contact 49 which is at the beginning of field or group 'A'. At this time also contact 52 engages brush 54 and continues in such engagement until the last index point position on the card passes the brush 43. If there is a perforation at "9" in the card the brush 43 will engage block 44 and a circuit will be set up as follows: From the supply leads 56 through wires 80, 86, contacts 89, wire 57, contacts 58 which, as set forth in my aforesaid application, are closed synchronously with the passage of the brush 43 over each index point position. These contacts may be timed to open just before the brush 43 is lifted from block 44 so that sparking due to breaking of the circuit will not occur at the said brush. From contacts 58 the current passes through wire 59, ring 45, brush 49, magnet 60, plug 61, to block 44, brushes 43, 54, segment 52, ring 53, brush 55 and back through wire 69 to the other side of the line. Relay 60 having become energized attracts its armature 64, releasing the upper arm 65 of contacts 66, which arm being pivoted at 67 and acted upon by spring 68 causes closure of the contacts 66. The closure of said contacts is so delayed by the inertia of the armature 64 and the distance traveled thereby before releasing arm 65 that the circuit is interrupted at contacts 58 before it has an opportunity of passing through the contacts 66. Obviously any other delayed action

device may be used to prevent contacts 66 closing in time to permit current to pass through magnet 15 while brush 43 is still in the first perforation. When a second perforation in the same column on the card now passes under brush 43, a new circuit will be set up as follows: From lines 56 through wire 80, contacts 89, wire 57, contacts 58, electromagnet 15, (brush 48 is now on insulation 47), contacts 66, plug 61, block 44, brushes 43, 54, segment 52, ring 53 and to the other side of the line.

The energization of magnet 15 will actuate armature 14 to release member 12 and permit the rod 11 to rise. This, as we have seen, will actuate hook 7 to actuate a type bar, impelling the same against the ribbon and platen to print the character carried by that bar. As indicated in the diagram, when index point "9" on the card is under the brush 43 the digit "9" in group A' will not have reached the active position represented by the index 70^a, so that, should the second perforation in the card be at index point "8," the digit "9" will then be at the printing position and will be printed. Similarly, if the second perforation is at any other of the index point positions the digit printed will be the next one higher than that punched in the card.

Should the first hole in the card be at any other point than "9" the contact 49 for group A' will have passed brush 48 and said brush will be on insulation 47 during the rest of the passage of the card through position A. Should the first hole be at index point "8", when this point reaches brush 43 at position B, the contact 49' associated with group B' will be in contact with brush 48 and brush 54 for position B will have engaged its segmental contact 52 so that magnet 60 will become energized, throwing magnet 15 into readiness for the next hole. If the second hole is at "7" the first character "0" in group B' will be printed. Or if the second perforation is at "6" printing of "A" will take place, etc. If the first hole is at "7" it will be detected at position C to select group C', etc., a first hole at "4" being detected at position F and selecting group F'.

It will be noted that each successive group has one less character than the preceding one, until group F', which is selected by a hole at point "4", has but four characters, there being only four index point positions to work from after "4" has been used, i. e., "3" to "0", inclusive.

It will be recognized that after a card has been read and before the next one reaches the reading positions, contacts 66 must be reset to open position. This may be effected by a cam 90 acting at the proper time upon the rod 91 having a collar 92 to rock arm 65 and permit spring 93 to move the locking armature 64 to operative position.

As will be seen, the segmental contacts 52 are successively shorter and are so arranged that each will make contact with its brush 54 only when the index point on the card representing the group selector for that particular sensing station reaches the respective brush 43, and breaks again as soon as the last index point on the card passes such brush.

The paper feeding mechanism is not disclosed here but may be the same as disclosed in the above mentioned application. In this connection it will be remembered that for each revolution of the type drum the paper will be stepped up one line space and one card will have been completely read and the data thereon printed. Thus, in the present case, the card will be fed through the several sensing positions while the type drum makes one revolution, and the paper feeding will take place after each such revolution. In this way, it will be seen, all of the data taken from a single card will be printed on one line.

Referring again to the contacts 58, it will be noted that several of these sets of contacts and means for operating them are shown. In this respect it should be understood that the several magnets 15 may be divided into groups, each group being connected to a separate one of said sets of contacts for the purpose of dividing the sparking due to circuit breaking between several sets of contacts.

What I claim is:

1. In a card-controlled machine, a rotatable drum, a plurality of groups of printing characters carried by said drum, group selector means controllable by a perforation in a card and a character selecting device 105 controllable by a perforation in a card and by said selector means for bringing one of said characters into printing operation.

2. In a card-controlled printing machine, a rotatable carrier, a plurality of printing 110 characters circumferentially arranged on said carrier, means adapted to bring one of said characters into printing operation while the carrier is rotating, and means controlled by a plurality of differently positioned holes 115 in a card for controlling said first named means.

3. In a record-controlled printing machine, a plurality of groups of type, record-controlled electrically actuated group selecting means, and electrically actuated means controlled by a record and by said selecting means for bringing one of said type into operation.

4. In a card-controlled printing machine, a plurality of groups of type, electrically actuated means controlled by a perforation in a card for selecting one of said groups, and means adapted to be rendered operative by said first named means and controlled 130

by a second perforation in the card for bringing a type of the selected group into printing operation.

5. In a card-controlled printing machine, a plurality of groups of type, group selecting means, means for actuating a type included in the selected group, means for closing a circuit through a hole in a card for actuating said group selecting means, and for closing a circuit through a second hole in the card for bringing said type actuating means into operation.

6. In a card-controlled printing machine, a plurality of groups of type, a plurality of card-perforation sensing stations, each of said stations corresponding to one of such groups, a group selecting device, perforation sensing means at each station, means for synchronizing the operativeness of each of 20 said sensing means with the passage of a card through the corresponding station for operating said device, and means rendered operative by said device and controlled by said sensing means for bringing one of said 25 type into printing operation.

7. In a card-controlled printing machine, a plurality of type, a plurality of sensing stations, means for feeding cards through said stations, each station being responsive 30 to a perforation in a separate predetermined position on a card, and type actuating means controlled through said stations.

8. In a card-controlled printing machine, a plurality of groups of type, a plurality of 35 card-perforation sensing stations, each of said stations corresponding to one of such groups, and adapted to control the operation thereof.

9. In a card-controlled machine, a plurality of intelligence characters, a plurality of card-reading stations, the several stations being adapted to control the operation of predetermined groups of said characters.

10. In a card-controlled machine, a plurality of type members, a type actuating element and means controlled by cards through a plurality of stations for operating said element.

11. In a card-controlled machine, a plurality of groups of type, a plurality of card-controlled group selecting stations and card-controlled type selecting means.

12. In a card-controlled machine, a plurality of groups of character elements, a plurality of card-controlled group selecting stations and card-controlled character element selecting means.

13. In a record-controlled printing machine, a plurality of type, a group selector including a perforation sensing element and a type selector also including said element, said group selector being adapted to determine the group of type from which the type selector shall select.

14. In a card-controlled printing machine,

a plurality of type, and a perforation sensing element adapted to successively cooperate with a plurality of perforations in a card to bring one of said type into operation.

15. In a tabulating machine adapted to be controlled by perforated cards, a plurality of type adapted to be controlled by perforations arranged in a column on a card, the type being greater in number than the possible number of perforations in a column of the card, and means adapted to be controlled by a card for bringing one of said type into operation.

16. In a card-controlled printing machine, a plurality of type, means for selectively causing printing operation of said type, and means adapted to cooperate with a plurality of perforations in a card for controlling said first named means.

17. In a card-controlled printing machine, a plurality of groups of type, a group selector, a type selector controlled by said group selector and adapted to cause a printing operation and means adapted upon cooperating with a perforation in a card to cause operation of said group selector, and upon cooperation with a second perforation in the card to cause operation of said type selector.

18. In a card-controlled machine, a plurality of groups of data-representing elements, means controlled by a perforation in a card for selecting one of said groups, said means being adapted upon cooperating with a second perforation in the card, to select one of the elements in the selected group.

19. In a card-controlled machine, a plurality of groups of data-representing elements, a sensing device adapted to cooperate with perforations in a card, a commutator unit, said device and unit operating conjointly to select one of said elements.

20. In a card-controlled machine, a plurality of groups of data-representing elements, a sensing device adapted to cooperate with perforations in a card, a commutator unit, said device and unit operating conjointly to select one of said elements, and means for recording the data represented by the element selected.

21. In a card-controlled machine, a plurality of groups of data-representing elements, a commutator unit corresponding with said groups, a plurality of card reading stations cooperating with said unit, each of said stations representing one of said groups and adapted conjointly with said unit to select a group, and means operative in response to such selection to cooperate with said stations to select one of said elements.

22. In a card controlled machine, means for continuously feeding cards through the machine, means for continuously advancing a series of type representing alphabetical characters to and past the printing position,

- means for sensing combination holes in said records while the latter are in motion and means controlled by the aforesaid sensing means for selectively calling the proper alphabetical type corresponding to the perforated combination into action as the type passes the printing point.
23. In a card controlled machine, in combination, means for continuously advancing a series of printing type towards and past a printing point, said types individually representing the letters of the alphabet, means for sensing combinational hole perforations in controlling records, and means controlled by the aforesaid means for selectively calling into printing action the type corresponding to the combination perforations.
24. In a card controlled machine having provisions for printing alphabetical characters upon a record sheet and means for sensing records having combinational holes while the records are in continuous motion through the machine and means controlled by the aforesaid sensing means for controlling the printing operations.
25. In a card controlled machine having, in combination, means for imprinting alphabetical characters upon a record sheet, said means including a plurality of type which are successively and continuously advanced forward and past the printing point, means for sensing perforated records having perforations therein designating the letters of the alphabet and means controlled by said sensing means for calling the corresponding type into action to effect printing.
26. A record controlled printing machine comprising means for electrically sensing combinational hole records, a printing means with provisions for printing the letters of the alphabet, and means controlled by said sensing means for controlling the operation of said printing means.
27. A record controlled machine having provisions for printing both alphabetical characters and numerals, means for continuously feeding combinational hole records through the machine, means for sensing the combinational holes in said records while the latter are in continuous motion, means for converting the combinational hole readings into differential linear readings and thereby controlling the printing operations.
28. In a machine of the character described, in combination with means for feeding record cards having a combinational hole system of index perforations, means to analyze the combinational designations of a multiplicity of characters simultaneously while the cards are in motion.
29. In a machine of the character described, in combination with means for feeding records having a combinational hole system of index perforations, a plurality of devices arranged to analyze the combinational designations of a multiplicity of characters simultaneously while the records are in motion.
30. In a machine of the character described, in combination with means for feeding cards having a combinational hole system of index perforations, a plurality of electric devices arranged to analyze the combinational designations of a multiplicity of characters simultaneously while the cards are in motion.
31. In a machine of the character described, in combination with means for feeding record cards having a combinational hole system of index perforations, and an electric means to analyze the combinational designations of a multiplicity of characters simultaneously while the cards are in motion.
32. In a record controlled machine, in combination with devices which are to be controlled in accordance with the designating values of combinational holes in record cards, of means for controlling said devices, said means including sensing brushes with provisions for simultaneously sensing a plurality of groups of combinational hole readings while the record cards are in motion.
33. In a combinational hole record controlled machine, in combination with devices which are to be controlled in accordance with the designating values of the combinational hole records, means for simultaneously reading a plurality of groups of combinational holes in the records while the latter are in motion, and means controlled by the aforesaid means for controlling the operation of the said devices.
34. A record controlled machine, including means for feeding combinational hole record cards and means including brush devices for simultaneously reading a plurality of groups of the combinational hole perforations while the record cards are in motion and controlling the operation of the parts of the machine in accordance with the derived reading.
35. A record controlled machine comprising in combination, means for feeding combinational hole records, printing devices, means for controlling the operation thereof, said means including devices for simultaneously sensing a plurality of character designating groups of the combinational holes while the records which contain said holes are in motion through the machine.
36. A record controlled machine comprising means for analyzing combinational hole readings of record cards while the cards are in motion, means for transposing said combination reading into a single reading, and means for establishing a circuit at a time period corresponding to the value of the combinational hole reading and to said single reading.
37. A record controlled machine compris-

ing means for analyzing combinational hole readings of record cards while the cards are in motion, means for transposing said combinational hole readings to control the timing of electrical circuits substantially for the purpose described.

38. A record controlled machine comprising card analyzing means for combinational hole readings, mechanism to be controlled according to the analyzed readings, magnets for controlling the same, circuit controlling devices therefor, and transposing devices having provisions for converting the combinational readings first to differential linear readings, and having provisions for subsequently utilizing said differential linear readings to control the circuit controlling devices for the aforesaid magnets; said card analyzing means being effective while the cards are in continuous motion through the machine.

39. In a record analyzing machine controlled by records on which characters may be designated by combinational index points, record analyzing means, means for feeding records into cooperative relationship to the analyzing means in the direction of spacing of the index points for a selected character and means controlled by said analyzing means while the records are in motion for converting the index points into a manifestation of the represented character.

40. In a record analyzing machine controlled by records on which characters may be designated by combinational index points, record analyzing means, means for feeding records into cooperative relationship to the analyzing means in the direction of spacing of the index points for a selected character and means controlled by said analyzing means while the records are in motion and passing through analyzing position for converting the index points into a manifestation of the represented character.

41. In a record analyzing machine controlled by records on which characters may be designated by combinational index points, record analyzing means comprising an individual mechanism for sensing one character designating field only on the record while the latter is in motion and means controlled by said analyzing means for manifesting the designated character.

42. In a record analyzing machine controlled by records on which letters of the alphabet may be represented by combinational index points, analyzing means for sensing the index points while the records are in motion and means controlled by the analyzing means for converting the index point designations into indications of the represented alphabetical characters.

43. In a record analyzing machine controlled by records on which letters of the alphabet may be represented by combina-

tional index points, electrical analyzing means for sensing the index points while the records are in motion and means controlled by said analyzing means for converting the index point designations into indications of the represented alphabetical characters.

44. A combinational index point record controlled machine comprising a plurality of groups of character manifesting elements, means responsive to certain index points for group selection, means responsive to other index points for character selection and analyzing means for sensing a record designation while the record is in motion to control said responsive means.

45. A combinational index point record controlled machine comprising a plurality of groups of character manifesting elements, means responsive to differentially located index points on a record for group selection and means responsive to index points differentially located with respect to the group index points for character selection.

46. A combinational index point record controlled machine comprising a plurality of groups of character manifesting elements, means responsive to differentially located index points on a record for group selection, means responsive to index points differentially located with respect to the group index points for character selection and analyzing means for sensing a record designation while the record is in motion for controlling said responsive means.

47. A combinational index point record controlled machine comprising a plurality of groups of character manifesting elements, analyzing means for successively sensing the controlling index points of a character designation, means controlled by said analyzing means and responsive to differential index point position and order of sensing for group selection and means controlled by said analyzing means and responsive to relative differential index point position and order of sensing for character selection.

48. A combinational index point record controlled machine comprising a plurality of groups of character manifesting elements, analyzing means for successively sensing the controlling index points of a character designation on a record while the record is in motion, means controlled by said analyzing means and responsive to differential index point position and order of sensing for group selection and means controlled by said analyzing means and responsive to relative differential index point position and order of sensing for character selection.

49. A combinational index point record controlled machine comprising a plurality of character manifesting elements, a plurality of analyzing stations, means for feeding a record successively past said stations, record analyzing means at each station and means

- controlled thereby in accordance with a controlling index point in a character designation for selecting one of said stations for record analysis and means controlled by the analyzing means at the selected station for initiating the operation of the designated character manifesting element. 65
50. A combinational index point record controlled machine comprising a plurality of groups of character manifesting elements, a plurality of analyzing stations one for each group, means for feeding a record successively past said stations, record analyzing means at each station and means controlled thereby in accordance with the differential location of the first index point of a character designation for selecting a station corresponding to the character group for record analysis and means controlled by the analyzing means at the selected station for initiating the operation of a character manifesting element in accordance with the differential location of subsequent index points in the character designation. 70
51. A combinational index point record controlled machine comprising a plurality of groups of character manifesting elements, a plurality of analyzing stations one for each group, means for feeding a record successively past said stations, record analyzing means at each station and means controlled thereby in accordance with the differential location of the first index point of a character designation for selecting a station corresponding to the character group for record analysis and means controlled by the analyzing means at the selected station in accordance with the location of subsequent index points with respect to said first named point for initiating the operation of a character manifesting element. 75
52. In a combinational index point record controlled machine, analyzing means for sensing a combinational index point designation while the records are in motion and means for converting said combinational reading into a time differential equivalent. 80
53. In a combinational index point record controlled machine, electrical analyzing means comprising sensing brushes for sensing a combinational index point designation while the records are in motion and electrical means comprising circuits controlled by said brushes and electrically operated mechanism controlled by said circuits for converting said combinational reading into a time differential equivalent. 85
54. A combinational index point record controlled machine comprising an analyzing station including individual analyzing means for searching each character designating field on a controlling record while the latter is in motion and means controlled by said analyzing means for converting the combinational index point character designations into time differential equivalents. 90
55. A combinational index point record controlled machine comprising an analyzing station including analyzing means for searching the character designating fields of a moving record, means for feeding records through the analyzing station in the direction of spacing of the combinational index points of a record field and means controlled by said analyzing means for manifesting represented characters. 95
56. In a combinational index point record controlled machine, analyzing means for sensing a combinational index point designation while the record is in motion, means controlled by said analyzing means for effecting a setup pertaining to the designation and means for converting said setup into a timed operation for manifesting said designation. 100
57. In a machine of the class described, analyzing means for sensing a combinational index point character designation during an operative machine cycle while the record bearing the designation is in motion, a control circuit and a cyclically operable timing device for controlling the time of energization thereof in accordance with the sensed designation and means controlled by the time of energization of said circuit for selectively indicating the designated character. 105
58. In a machine of the class described, analyzing means for sensing a combinational index point designation on a controlling record while the record is in motion, cyclically operable indicating means manifesting in different positions different possible characters on a character designating record field, electrical timing means controlled in its operation by a sensed combination on the controlling record and selective means controlled by said timing means for selecting a manifesting position of said indicating means corresponding to a sensed character designation. 110
59. In a machine of the class described, electrical analyzing means for sensing a combinational index point character designation on a controlling record while the record is in motion, cyclically operable indicating means manifesting in different positions different possible characters on a character designating record field, electrical timing means controlled in its operation by a sensed combination on the controlling record and selective means controlled by said timing means for selecting a manifesting position of said indicating means corresponding to a sensed character designation. 115
